UNITED STATES PATENT OFFICE.

ELBERT S. DODGE, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed June 2, 1923. Serial No. 642,891.

To all whom it may concern:

Be it known that I, ELBERT S. DODGE, a citizen of the United States, and resident of Ilion, in the county of Herkimer and State 5 of New York, have invented certain new and useful Improvements in Typewriting Machines, of which the following is a specification.

My invention relates to typewriting machines, and more particularly to tabulator mechanism.

The main object of the invention, generally stated, is to provide simple, strong and efficient tabulator mechanism.

Another object of my invention is to provide a simple, strong and efficient single key tabulator which may, when desired, be readily embodied in standard Remington machines as a substitute for the tabulator 15 mechanisms now employed therein without material modification of such machine except such as are effected by the substitution of one character of tabulator for another.

Still another object of my invention is to 25 provide strong and reliable mechanism for preventing a rebound of the carriage when it is arrested by its tabulator stops.

To the above and other ends which will hereinafter appear, my invention consists in 30 the features of construction, arrangements of parts and combinations of devices set forth in the following description and particularly pointed out in the appended claims.

In the accompanying drawings, wherein like reference characters indicate corresponding parts in the various views,

Figure 1 is a fragmentary fore-and-aft vertical sectional view of a typewriting machine embodying my invention.

Figure 2 is a detail front elevation of a portion of the tabulator mechanism and some of the associated parts.

Figure 3 is a fragmentary detail top plan view, with parts in section, of the key controlled means by which the tabulator is actuated.

Figure 4 is a detail fragmentary top plan view of the key actuated stop and some of the associated parts; the view showing the parts in actuated position with the cover plate of the housing removed.

I have shown my invention in the present instance embodied in a standard Remington

machine, but have illustrated only so much 55 of said machine as is necessary to arrive at an understanding of my invention in its embodiment therein. While the invention may be readily incorporated as a substitute for the tabulator mechanism, either column or 60 decimal selectors, now employed in such machines, it should be understood that the invention is not restricted to its use therein but may be employed in typewriting or like machines generally and wherever found 65 available.

The frame of the machine comprises a base 10, corner posts 11 and top plate 12.

A power driven carriage 13 of the usual construction is mounted on rollers, including the rollers 14, to travel over the top plate from side to side of the machine. Extending rearwardly from and fixed to the carriage are bracket arms 15, which support the usual column stop bar 16 on which column stops 17 are mounted. The column stops in the present instance are situated at letter space intervals on the stop bar and may be shifted individually rearwardly on the bar from the inoperative position, indicated by the foremost stop 17 in Fig. 1, to the operative position, indicated by the stop in the rear thereof in this view.

A feed rack 18 is mounted on the carriage in the usual manner, being carried on arms 19 pivoted at 20 on the carriage. The feed rack is normally spring pressed down into effective position where it engages a feed pinion 21. The feed pinion is mounted on a shaft (not shown) supported in a bracket 22 fixedly supported above the top plate of the machine. Said shaft is operatively connected at its rear end to an escapement wheel 23, controlled in the usual manner to afford a step-by-step letter feed movement 95 of the feed pinion 21 and the carriage controlled thereby.

In the usual standard Remington machines the carriage is released at each tabulating operation by the combined carriage release and retarding device constructed and operated as follows:

A sheet metal frame 24 is pivoted at 25 to swing on a bracket 26 secured to the top plate of the machine. This frame 24 105 has a portion 27 formed with bearing openings to receive a shaft 28 that is adapted to turn therein. The forward end of this

shaft carries a pinion 29, and the rear end thereof is connected in the usual manner with a member of a retarding device that turns in a body of shot contained 5 within a drum 30 secured to the frame 24 by screws 31. The frame 24 is pivotally connected at 32 to a depending link 33 that has its lower end pivoted at 34 to a crank arm 35 fixed on a rock shaft 36. 10 This rock shaft is mounted at its ends in brackets 37 secured by bolts 38 and nuts 39 to the base 10 of the machine. The crank arm 35 is also pivotally connected at 40 to a forwardly extending link 41 15 pivoted at its forward end, as indicated at 42, to a depending ear 43 on a universal release bar 44. A second link 41^a is connected in a like manner at its forward end to the universal release bar near the left- 20 hand end thereof; the rear end of the link being connected to a second depending crank arm 35^a on the left-hand end of the rock shaft 36. Said release bar is provided with upturned ends 45 pivoted on 25 a cross bar 46 supported at its ends in the base of the machine. A contractile spring 47 is connected at one end to the universal release bar and at its other end to a key stem guide 48, to return the universal bar and the parts connected therewith to normal position.

In standard Remington machines a series of key controlled angular levers 49 are mounted to turn on the cross bar or 30 pivot rod 46. The rear edges of the depending arms 50 of said levers coact with the forward edge of the universal release bar to actuate it, and thereby swing the frame 24 and release the feed rack from its pinion; at the same time connecting the retarding device with the feed rack to retard the free movement of the carriage.

In said standard Remington machines each lever 49 is connected with a key stem 35 movable vertically in guide openings 52 and 53 in guides 54 and 48 respectively; each key stem being provided with a tabulator key at the upper end thereof. Moreover, in such construction, the depending 40 arm 50 of each lever 49 is connected with a rearwardly extending link, that in turn is connected at its rear end to a tabulator lever carried in a tabulator frame for controlling a tabulator stop. In the present 45 construction I eliminate the usual tabulator frame, the tabulator levers, the stops controlled thereby and the link connections between the levers 49 and the tabulator levers. Moreover, I use but two of the widely 50 separated levers 49 of the usual series. These two levers are maintained properly positioned and spaced apart on the rod 46 by collars 55 held on the rod by set screws 56. The key stems 51 connected to said 55 levers are united at their upper ends by

a single wide tabulator key 57 arranged in the rear of the last row of printing keys 58 in the keyboard.

As far as has been described, an actuation of the tabulator key merely actuates 70 the combined carriage releasing and retarding device to free the carriage from control of its escapement mechanism. In accordance with my present invention I utilize the actuation of the releasing device 75 to transmit motion to the tabulator stop, and to the anti-rebound detent of my invention, now about to be described.

It will be seen that the frame 24 is provided with an upwardly extending ear 59 80 in which is received the forward bent end of a connecting link 60; the rear bent end of this link extending through an opening 61 in a crank arm 62. This crank arm has its hub fixed to a rock shaft 63, 85 the arm extending downwardly from said shaft and controlling its rocking movement. The shaft receives its support in bearing openings in a special casting, housing or tabulator frame 64, and is held 90 against endwise displacement in said bearings by collars 63^a held on the shaft by screws and coacting with the inner side walls of the housing. The housing 64 is secured by screws 64^a to a top plate of 95 the machine and has a cover plate 65 detachably secured thereto by screws 66. Contained within the housing 64, and fixed to the rock shaft 63, is an upwardly projecting crank arm 67 rounded at its upper 100 end, as indicated at 68 in Fig. 1. This arm is returned to and normally held in the Fig. 1 position by a spring 69. The upper rounded end of the arm 67 is seated in the bearing slot 70 in a slide or stop 105 carrier 71. In the present instance this member 71 is in the nature of a block mounted in a depression 72 in the upper side of the housing beneath the cover plate 65. The member 71 is guided by the walls 110 of said depression for horizontal sliding movement fore-and-aft of the machine from the Fig. 1 to the Fig. 2 position. The upper side of the member 71 has a transversely extending depression 73 therein in 115 which is received a transversely extending stop bar 74. Said bar is fixed at its ends by screws 75 in depressions in the upper face of the housing beneath the cover plate 65. This bar coacts with the rear and front 120 walls respectively of the depression 73 to limit the fore-and-aft sliding movements of the member 71.

The member 71 is provided with an integral forwardly projecting tabulator stop 125 76 formed with a right-hand flat face with which an operative column stop 17 is adapted to co-act to arrest the travel of the carriage in its movement from right to left, as will hereinafter more clearly appear. The slide 130

71 carries an anti-rebound pawl, detent, latch, catch or lock, which in the present instance is constructed as follows: A cutout 77 is formed in the forward edge of the 5 member 71 to receive an anti-rebound detent member, block or slide 78, that is guided in its fore-and-aft movement independently of the slide 71 by the walls of said cutout. The slide 78 is provided with a transversely extending depression 79 in the upper side thereof which is adapted to register with the depression 73 in the slide 71. The stop bar 74 extends through the depression 79, although a separate stop pin 80 is carried by 10 the slide 78 to coat with the slide 71, and thereby limit the forward movement of the slide 78 relatively to the member 71. The forward edge of the slide 78 is beveled or inclined rearwardly from left to right, as indicated at 81 in Fig. 4. The left-hand end of the beveled edge terminates in an abrupt rearwardly extending engaging face 82 adapted to be projected behind, or to the right of, a column stop 17, as shown in Fig. 15 4. In this position the detent prevents a rebound of the carriage as the stop 17 coats with the key controlled tabulator stop 76. A coiled expansion spring 83 bears at one 20 end against the slide 71 and at its other end against the slide 78, to normally maintain said slide 78 in the position shown in full lines in Fig. 4, relatively to the slide 71. In actuating the tabulator the operator depresses the key 57, thereby transmitting a 25 swinging motion to the frame 24 which is effective to release the carriage. The swinging motion of the frame also actuates the rock shaft 63 through the link 60. The rocking motion of the shaft shifts the arm 67 and 30 slides the member 71 forward to bring the stop 76 thereon into the path of the operative column stop 17. The anti-rebound detent member 78 at this time moves forward with the member 71 to the full line position 35 in Fig. 4. The carriage having been released will advance to the left carrying the rear edge of the first operative column stop 17 into contact with the bevel 81 on the member 78. As the carriage advances 40 further to the left the action of the engaging stop 17 with the bevel 81 cams the member 78 rearwardly to the dotted line position in Fig. 4. When the column stop passes the bevel and reaches the position 45 shown in this figure, the force of the spring 83 is effective to snap the detent forward to the full line position, thereby bringing the stop face 82 on the detent behind the arrested column stop 17. The arrest of the 50 carriage having been thus effected the tabulator key 57 is released and the springs 47 and 69 are effective to return the key 57 and the parts controlled thereby to normal position. This re-establishes connection between 55 the feed rack 18 and the feed pinion 21, and

carries the detent members 78 back with the slide 71, withdrawing the parts 76 and 82 from engagement with the coating column stop 17.

It will be observed that by my invention I have provided a simple, strong and effective tabulator and anti-rebound construction that may be readily embodied in standard Remington machines without material modification of said machines, except to substitute devices of my invention for those now in use. It will be understood, moreover, that I have utilized parts that are now embodied in such machines to coat in a novel manner with the devices I have substituted for those ordinarily used. It will be seen, therefore, that the tabulator mechanism of the present invention may be readily employed, when desired, as a substitute for the ordinary constructions, at comparatively small cost.

What I claim as new and desire to secure by Letters Patent:

1. In a typewriting machine, the combination of a carriage, a column stop carried thereby, a key controlled sliding block carrying a co-acting tabulator stop and supported by the frame of the machine and adapted by the sliding movement thereof to project its stop into the path of movement of the column stop, an anti-rebound detent mounted on said block for movement therewith and for independent sliding movement thereon, and a spring between said block and detent and which tends to maintain the normal relation between the two and cause them to travel together and to force the detent to engaging position behind said column stop when the latter is engaged by the key controlled tabulator stop.

2. In a typewriting machine, the combination of a carriage, a series of adjustable column stops carried thereby, a key controlled combined carriage releasing and carriage retarding device including a swinging frame controlled by said key, a sliding carrier connected with and moved by said swinging frame, a single tabulator stop carried by said carrier and projected by the sliding movement of the latter into the path of said column stops, and a spring pressed anti-rebound detent mounted for sliding movement on said carrier.

3. In a typewriting machine, the combination of a tabulator key arranged at the rear of the keyboard of the machine, a pair of angular levers actuated by said key, a universal carriage release bar with which said angular levers coat, a carriage releasing device actuated by said universal release bar, a tabulator stop operatively connected to said releasing device and projected thereby to operative position, and a carriage carried column stop coacting with said tabulator stop.

4. In a typewriting machine, the combination of a tabulator key arranged at the rear of the keyboard of the machine, a pair of angular levers actuated by said key, a universal carriage release bar with which said angular levers coact, a carriage releasing device actuated by said universal release bar and comprising a swinging frame, a rock shaft, a link connecting said swinging frame and rock shaft, a tabulator stop controlled by said rock shaft, and a co-operative carriage carried column stop. 5
5. In a typewriting machine, the combination of a carriage, a column stop carried thereby, a key, a carriage releasing device including a swinging frame controlled by said key, a rock shaft controlled by said frame, a slide controlled by said rock shaft, and a tabulator stop on said slide and co-operative with said column stop. 10
- 15 6. In a typewriting machine, the combination of a carriage, a column stop carried thereby, a key, a carriage releasing device including a swinging frame controlled by said key, a rock shaft, a link between said frame and shaft to effect an actuation of said shaft by the frame, a crank arm on said shaft, a sliding carrier controlled by said crank arm, and a tabulator stop formed as a part of said carrier and co-operative with said column stop. 20
- 25 7. In a typewriting machine, the combination of a carriage, a column stop carried thereby, a key, a carriage releasing device including a movable frame controlled by said key, a rock shaft controlled by said frame, a crank arm on said shaft, a sliding carrier controlled by said crank arm, a tabulator stop carried by the carrier and co-operative with said column stop, and an anti-rebound detent, carried by and adapted to slide relatively to said carrier and to engage behind said column stop when the latter is arrested by the tabulator stop. 30
- 35 8. In a typewriting machine, the combination of a carriage, a column stop carried thereby, a key, a carriage releasing device including a swinging frame controlled by said key, a rock shaft controlled by said frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 40
- 45 9. In a typewriting machine, the combination of a tabulator key arranged at the rear of the keyboard of the machine, a pair of angular levers actuated by said key, a universal carriage release bar with which said angular levers coact, a combined carriage releasing and retarding device including a swinging frame controlled by said key, a rock shaft controlled by said swinging frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 50
- 55 10. In a typewriting machine, the combination of a carriage, a column stop carried thereby, a key, a carriage releasing device including a swinging frame controlled by said key, a rock shaft controlled by said frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 60
- 65 11. In a typewriting machine, the combination of a carriage, a column stop carried thereby, a key, a carriage releasing device including a swinging frame controlled by said key, a rock shaft controlled by said frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 70
- 75 12. In a typewriting machine, the combination of a carriage, a column stop carried thereby, a key, a carriage releasing device including a swinging frame controlled by said key, a rock shaft controlled by said frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 80
- 85 13. In a typewriting machine, the combination of a carriage, a column stop carried thereby, a key, a carriage releasing device including a swinging frame controlled by said key, a rock shaft controlled by said frame, a crank arm on said shaft, a sliding carrier engaged and controlled by said crank arm, an integral tabulator stop carried by the carrier and co-operative with said column stop, and a spring pressed anti-rebound detent carried by and adapted to slide relatively to said carrier and to engage behind said column stop when the latter is arrested by the tabulator stop. 90
